UNITED STATES PATENT OFFICE.

FERDINAND RUSTANT, OF SAN FRANCISCO, CALIFORNIA.

NON-REFILLABLE BOTTLE.

1,357,654.

Specification of Letters Patent.

Patented Nov. 2, 1920.

Application filed March 16, 1920. Serial No. 366,297.

To all whom it may concern:

Be it known that I, FERDINAND RUSTANT, a citizen of the United States, residing at San Francisco, in the county of San Francisco and State of California, have invented certain new and useful Improvements in Non-Refillable Bottles, of which the following is a specification, reference being had therein to the accompanying drawings.

This invention relates to nonrefillable bottles, and has for its object the provision of efficient valve means whereby the liquid contained in the bottle can be discharged, but the bottle cannot be fraudulently refilled.

Another object of the invention is the provision of efficient ball and sliding valve means whereby liquid cannot be fraudulently inserted in the body of a bottle constructed in accordance with the present invention.

With these and other objects in view, my invention comprises certain novel constructions, combinations, and arrangements of parts as will be hereinafter specifically described, illustrated in the accompanying drawings, and more particularly pointed out in the appended claims.

In the drawings,

Figure 1 is a vertical sectional view through a bottle neck, showing my improved valve means, constructed in accordance with the present invention.

Fig. 2 is a vertical sectional view taken on line 2—2, Fig. 1, looking in the direction of the arrows.

Fig. 3 is a sectional view taken on line 3—3, Fig. 1, looking in the direction of the arrows.

Fig. 4 is a perspective view of the sliding valve device.

Fig. 5 is an inverted perspective view of the spring holder.

Referring to the drawings by numerals, 1 designates the body of the receptacle or bottle and 2 is the neck. In the neck is formed the primary passage portion 3 which communicates with the right-angularly-disposed passage portion 4, and the passage

portion 4 communicates with the substantially U-shaped portion 5; the outer upper end 6 of the U-shaped portion 5 communicates with the outer valve portion 7; these portions 3, 4, 5, 6, and 7 constitute a peculiarly-constructed liquid passage formed in the neck 2 of the receptacle or bottle.

The inner end of the passage portion 3 communicates with the interior of the receptacle body 1, but its inner or upper end is closed to receive the concavo-convex spring holder 8, which spring holder is provided with a depending socket 9 that receives the upper end of coil spring 10. The coil spring 10 rests in a socket or notch 11 of the crystal or ball valve 12, so that the action of the spring 10 is positive upon the ball valve 12 for retaining the same in its normal seated position (Fig. 1).

Upon opposite sides of the passage portion 3 are formed guide slots 13, which slots 13 receive the ends 15 of the weight 16, which weight bears at its upper end 17 against the ball valve 12, so that when the bottle is tilted, the weight 16 will slide against the valve to overcome the strain of spring 10 upon the ball, causing the ball to move to the position shown in Fig. 2, or by dotted line in Fig. 1, thereby permitting the liquid to pass from the bottle, but as soon as the bottle is moved to an upright position, the ball valve 12 is seated by the action of the spring, the weight 16 drops by gravity to its lowest position as shown in Fig. 1, allowing valve 12 to move to its seated position, in which position the fraudulent refilling of the bottle is prevented.

The primary valve device comprises the sliding frame 18, which frame 18 is mounted in a slot (Fig. 1), and this slot is in alinement with the socket 19; the upper end 90 of the frame 18 enters the slot 19 when the bottle is tilted or in an inverted position. The frame 18 is provided with an outlet opening 20, and pivotally mounted at 21 upon the frame is a gate or valve 22 that 95 closes when the bottle closes, when an attempt is being made to fraudulently refill the bottle, but the hinged valve 22 falls outwardly, as shown in dotted lines in Fig. 1, to permit the liquid to pass from the 100 bottle when it is desired to discharge the liquid. The upper end of the valve 22 engages a shoulder 23 on frame 18, when the valve 22 is closed.

From the foregoing description, it will be understood that I have constructed a non-refillable bottle with a peculiar primary valve device, as well as a peculiar auxiliary valve device, and these two devices coöperate for the prevention of fraudulent 110 refilling of the bottle, and certain minor alterations or changes may appear to one

skilled in the art to which my invention relates, in the construction of said invention, and I reserve the right to make such minor alterations or changes as shall fairly fall 5 within the scope of the appended claims.

What I claim is:

1. In a nonrefillable bottle, the combination of a neck provided with a liquid passage, a ball mounted in said liquid passage, 10 a concavo-convex spring holder in said passage, a spring in said passage and engaging said spring holder and said ball for normally retaining the holder in a seated position, means for assisting in unseating said ball, and auxiliary valve means carried by the neck and adapted to extend across said liquid passage.
2. In a nonrefillable bottle, the combination of a neck provided with a liquid passage including a primary passage portion, a ball valve in said primary liquid passage portion, a concavo-convex spring holder seated snugly in the inner end of said primary liquid passage portion, said spring 25 holder provided with a depending socket, said ball provided with a socket, a coil spring having one end seated in the socket of the

spring holder and its other end in the socket of the ball, means for forcing the ball to an unseated position and overcoming the strain of the spring when the holder is tilted or inverted, and an auxiliary valve device 30 slidably mounted in the holder and coöperating with said ball for positively closing the passage against fraudulent refilling when the ball is in an open or unseated position.

3. In a nonrefillable bottle, the combination of a bottle neck provided with a liquid passage, said liquid passage including a spring holder seat, a spring holder in said 40 seat, a movable valve in said passage and adapted to move into said spring holder, a spring positioned at one end in said spring holder and at its opposite end in said valve, a sliding weight in said liquid passage and 45 acting upon said valve, and auxiliary valve means carried by the neck and adapted to close the passage against the fraudulent refilling when said first-mentioned valve is in an unseated position.

In testimony whereof I hereunto affix my signature.

FERDINAND RUSTANT.
